UNITED STATES PATENT OFFICE.

BERNARD D'ESCAYRAC, OF NEW YORK, N. Y., ASSIGNOR TO GUERLAIN PERFUMERY CORPORATION OF NEW YORK, OF NEW YORK, N. Y., A CORPORATION OF NEW YORK.

DESIGN FOR A BOX OR SIMILAR CONTAINER FOR A BOTTLE.

Application filed January 26, 1928. Serial No. 25,046. Term of patent 14 years.

To all whom it may concern:

Be it known that BERNARD D'ESCAYRAC, a citizen of the Republic of France, now residing at No. 33 West 55th Street, borough of Manhattan, city, county, and State of New York, has invented a new, original, and ornamental Design for a Box or Similar Container for a Bottle, of which the following is a specification, reference being had to the accompanying drawings, forming part thereof:

I claim:

The ornamental design for a box or similar container for a bottle substantially as shown.

BERNARD D'ESCAYRAC.
